UNITED STATES PATENT OFFICE.

BURTON S. AIKMAN, OF MILWAUKEE, WISCONSIN, ASSIGNOR TO NATIONAL BRAKE & ELECTRIC COMPANY, OF MILWAUKEE, WISCONSIN, A CORPORATION OF WISCONSIN.

SELF-CLEANING STRAINER AND MUFFLER.

1,073,883.

Specification of Letters Patent. Patented Sept. 23, 1913.

Application filed January 13, 1913. Serial No. 741,699.

To all whom it may concern:

Be it known that I, BURTON S. AIKMAN, a citizen of the United States, residing at Milwaukee, in the county of Milwaukee and State of Wisconsin, have invented certain new and useful Improvements in Self-Cleaning Strainers and Mufflers, of which the following is a full, clear, concise, and exact description, reference being had to the accompanying drawing, forming a part of this specification.

My invention relates to compressed air systems and consists of a self cleaning strainer and muffler for use in conjunction with such systems.

My invention is of great utility in connection with compressed air systems employed in conjunction with railroads. It is well known that the compressors used in such systems are liable to be clogged with dirt or dust drawn in from the atmosphere as the trains or cars pass through districts or zones where there is a great deal of dust.

My invention is designed to strain the air before it is drawn into the compressor and, in addition, it serves as a muffler, thus preventing undue noise as the exhaust air is expelled from the brake valves.

My invention will be better understood by referring to the accompanying drawing which illustrates my invention having suitable connections to the compressor as well as to the pipes leading to the brake valves.

The arrangement embodying my invention comprises a casing 1 which has a connection 2 which leads to and is connected with an extension 3 of a compressor. The casing 1 has also suitably connected therewith piping 4 which extends from the brake valves. The casing is provided at its upper portion with a plurality of arms 5-5 which support a central member 6 in such a way as to leave a plurality of openings 7 between the arms. The member 6 is threaded as shown and is adapted to receive a neck portion 8 of a drum 9. Between this drum and lower portion of the casing there is disposed a suitable gasket 10. This drum is hollow as shown and opens into the atmosphere at its lower portion. The drum is of more or less skeleton form and consists of a plurality of ribs 11-11 between which there are openings 12-12. The central portion of the drum having an annular bearing surface

13-13 and the upper portion having a bearing surface 14. A similar surface is provided at the lower portion shown at 15. These surfaces have bearing engagement with a screen 16, which screen is surrounded by fabric or cloth 17 of large mesh. The cloth and screen are held in place by suitable metal bands 18-18 as shown. The lower portion of the drum is spanned by member 19 which serves as a suitable member for the engagement of a tool in order to screw the drum into place.

When the compressor, which is used in conjunction with an air compressing system, is working the air which is drawn through the opening in the lower portion of the drum 70 passes through the screen 16, the cloth 17 and through the member 2 into the member 3 and past a valve 20 which is in an open position when the compressor is working. This air is drawn in at a low velocity so 75 that as it passes through the screen and cloth all of the dust is removed from the air so that it is prevented from passing into the compressor. After a certain amount of air has passed through the compressor and the 80 air pressure reaches a predetermined point in the tank connected with the compressor, the flow of air will cease. In other words, the compressor will not create any further suction after the maximum air pressure in 85 the tank has been reached.

When the air exhausts from the brake valves and passes through the pipes 4-4 it passes through the openings 7-7 at a high velocity and strikes the fabric 17 and 90 passes therethrough as well as the screen 16, thus removing any dust which has collected on these two members, which dust is forced into the atmosphere. In addition to this the screen 16 and the fabric 17 act as a muffler 95 so that the exhaust from the brake valves is scarcely audible. My purpose in providing the fabric 17 of open mesh is so that the dust fastens itself very readily to the cloth and it is thus prevented from entering 100 the compressor during its operation.

The drum as shown is constructed so that when necessity requires, it may be readily removed by applying a suitable tool to the member 19.

One important feature of my invention is the fact that after a certain amount of air has been drawn into the compressor through

the screen and fabric 17 which have collected dirt or dust, the next operation cleans these two members, owing to the fact that the exhaust from the brake valves is forced through these members, thus completely cleaning them and forcing the dust laden air into the atmosphere.

It will be observed from the foregoing description that my invention comprises 10 very effective means for preventing dust from entering the compressor as well as preventing a great deal of noise when the exhaust air is expelled from the brake valves.

The muffler arrangement in itself is very 15 important since it is well known that in compressed air systems as used in railroad work there is considerable noise when the exhaust air passes from the brake valves.

While I have herein shown and described 20 one particular embodiment of my invention, I do not wish to be limited to the precise details shown and described, but desire to secure protection upon any equivalent construction which will be apparent to those 25 skilled in the art.

What I claim is:

1. In a device of the class described, the combination of a casing having connections to the intake and exhaust of a compressed 30 air system, and means in said casing for straining the air, said means also serving as a muffler for the exhaust air.

2. In a device of the class described, the combination of a casing having connections 35 with the intake and exhaust of a compressed air system, and means in said casing for straining the air, said means comprising a metallic screen and fabric around said screen.

40 3. In a device of the class described, the combination of a casing communicating with the atmosphere, said casing having connections with inlet and outlet openings in a compressed air system, and mechanism in 45 said casing for straining the air, said mechanism comprising a metallic screen and a fabric of large mesh disposed around said screen.

4. In a device of the class described, the 50 combination of a casing having communication with the atmosphere, said casing having connection with a compressor of an air brake system, said casing also having a connection with the exhaust from the brake 55 valves, and screening apparatus disposed in said casing for straining the air before it passes into the compressor, said screening apparatus also serving as a muffler for the exhaust air from the brake valves.

60 5. In a device of the class described, the combination of a casing having communication with the atmosphere, said casing having a connection with a compressor of an air brake system, said casing also having 65 a connection with the exhaust from the

brake valves, and screening apparatus mounted in said casing for straining the air before it passes into the compressor, said screening apparatus also serving as a muffler for the exhaust air from the brake valves, 70 said screening apparatus consisting of a metallic screen and a fabric of wide mesh.

6. In a device of the class described, the combination of a casing having communication with the atmosphere, said casing having a connection with a compressor of an air brake system, said casing also having a connection with the exhaust from the brake valves of such system, and a plurality of 80 the air straining members disposed in said casing, said members also serving as a muffler for the exhaust air from the brake valves.

7. In a device of the class described the combination of a casing having communication with the atmosphere, said casing having a connection with a compressor of an air brake system, said casing also having a connection with the exhaust from the brake 85 valves of such system, and a plurality of 90 the air straining members disposed in said casing, said members also serving as a muffler for the exhaust air from the brake valves, said members being arranged to be removed from said casing.

8. In a device of the class described, the combination of a casing having connections with the intake and exhaust of a compressed air system, and means in said casing for straining the air.

9. In a device of the class described, the combination of a casing having two connections, one leading to the intake of a compressed air system, and the other leading to the exhaust valves of said system, and a device in said casing for straining the air.

10. In a device of the class described, the combination of a casing having a connection to the intake of a compressed air system and another connection to the exhaust valves of such system, and a device in said casing for straining the air.

11. In a device of the class described, the combination of a casing having a connection to the intake of a compressed air system and another connection to the exhaust valves of such system, and a removable device in said casing for straining the air.

12. In a device of the class described, the combination of a casing having a connection to the intake of a compressed air system and another connection to the exhaust valves of such system, and a device in said casing through which the air is drawn and exhausted, said device comprising a hollow drum provided with openings, and a screen mounted on said drum and over said openings, said drum being open at one end to the atmosphere.

13. In a device of the class described, the

combination of a casing having a connection to the intake of a compressed air system and another connection to the exhaust valves of such system, a hollow member removably fastened in said casing through which the air is drawn and exhausted, said member having openings therethrough, and screening members disposed over said openings, said hollow member having one end open to the atmosphere.

14. In a device of the class described, the combination of a casing having a connection to the intake of a compressed air system and another connection to the exhaust valves of such system, a hollow member removably fastened in said casing through which the air is drawn and exhausted, said member having openings therethrough, screening members disposed over said openings, and

devices for holding said screening members in place.

15. In a device of the class described, the combination of a casing having a connection to the intake of a compressed air system and another connection to the exhaust valves of such system, a hollow member removably fastened in said casing through which the air is drawn and exhausted, said member having openings therethrough, screening members disposed over said openings, and bands for holding said screening members in place.

In witness whereof, I hereunto subscribe my name this 10th day of Jan., A. D. 1913.

BURTON S. AIKMAN.
